UNITED STATES PATENT OFFICE.

GEORGE A. MOWREY, OF MILLVALE, PENNSYLVANIA.

DESIGN FOR A SPOOL-HOLDER.

41,860.

Specification for Design.

Patented Oct. 24, 1911.

Application filed March 24, 1911. Serial No. 616,776. Term of patent 3½ years.

To all whom it may concern:

Be it known that I, GEORGE A. MOWREY, a citizen of the United States, residing at Millvale, in the county of Allegheny and State of Pennsylvania, have invented a certain new, original, and ornamental Design for a Spool-Holder, of which the following is the specification, reference being had to the accompanying drawing, forming a part thereof.

The figure is a perspective view of the spool holder, illustrating my new design.

I claim:

The ornamental design for a spool holder, as shown.

GEORGE A. MOWREY.

Witnesses:

MAX H. SROLOVITZ,
CHRISTINA T. HOOD.
